[57] **CLAIM**

The ornamental design for a piezoelectrically ignited portable propane gas hand torch, as shown and described.

DESCRIPTION

FIG. 1 is a perspective view of a piezoelectrically ignited portable propane gas hand torch, embodying my new design;

FIG. 2 is a top plan view thereof;

FIG. 3 is a side elevation view thereof;

FIG. 4 is an end elevation view thereof, viewed from the left of FIG. 3;

FIG. 5 is an end elevation view thereof, viewed from the right of FIG. 3; and

FIG. 6 is a bottom plan view thereof.
